(57) **CLAIM**

The ornamental design for an illumination device, as shown and described.

DESCRIPTION

FIG. 1 is a front view of an illumination device showing my new design;

FIG. 2 is a rear view of the illumination device;

FIG. 3 is a left side view of the illumination device;

FIG. 4 is a top view of the illumination device;

FIG. 5 is a bottom view of the illumination device; and,

FIG. 6 is a right side view of the illumination device.

The broken line showing is for environmental purposes only and forms no part of the claimed design.
